EGG CLEANING DEVICE

Leonard S. Crammer and Manuel Ferreira,
Alameda County, Calif.

Application January 24, 1948, Serial No. 4,198

6 Claims. (Cl. 51—3)

1

This invention relates to egg cleaning devices, and has for its principal object the provision of a machine adapted to facilitate egg cleaning operations prior to packaging and shipment to market.

A further object of the invention is the provision of a device of the class described, which is adjustable in order to accommodate eggs of various sizes.

A still further object of the invention is the provision of a device adapted to speedy handling of eggs that are only slightly soiled.

A still further object of the invention is the provision of a machine in which all the moving parts are readily accessible for inspection or repair.

The above and other objects of the invention will become apparent during the course of the following description taken in connection with the accompanying drawings, forming a part hereof, and in which:

Figure 1 is a side elevation of a preferred embodiment of our invention;

Figure 2 is a section taken on line 2—2 of Figure 1;

Figure 3 is a plan view of the device with the top removed, and as viewed from line 3—3 of Figure 2;

Figure 4 is an enlarged section of the buffing wheel taken on line 4—4 of Figure 1;

Figure 5 is an enlarged section of the egg rotating spindles taken on line 5—5 of Figure 1;

Figure 6 is a fragmentary detail showing how an egg is mounted in the chucks;

Figure 7 is a fragmentary detail illustrating how the end of an egg is cleaned on the device;

Figure 8 is a perspective view of a buffing pad;

Figure 9 is an enlarged section of the end buffer taken on line 9—9 of Figure 5.

Referring to the drawings in detail, an open-bottomed boxlike structure is shown, comprising four sides 10 secured at their adjacent corners by legs 11. Hingedly mounted to one of the sides 10 is a cover 12, which forms a base for the elements mounted on the upper side thereof. Other parts of the device are also mounted on the under side of the cover 12, as will be described herein.

Depending from the under side of the cover 12 are two parallel, vertical panels 13, spaced apart, and connected at their lower edges by a shelf 14 which normally lies in a horizontal plane. The panels 13 are formed, as is shown by numeral 15 on Figure 1, in order that they may

2

clear the sides 10 when the cover 12 is raised as indicated in phantom on Figure 1. This feature of the device permits of ready inspection and access to all moving parts, without dismantling or inverting the machine as a whole.

A driving motor M is mounted on the shelf 14 between the panels 13, and provides the motive power for a buffing wheel shaft 16, and a driving chuck spindle 17. A driving pulley 18, mounted on the motor M, transmits motion through the medium of a belt 19 to a driven pulley 20 which is mounted on an idler shaft 21. Motion is further transmitted from the idler shaft 21, by means of pulleys 22 and 23, and belt 24, to the driving chuck spindle 17. Motion is also transmitted, from the idler shaft 21, by means of pulleys 25 and 26, and belt 27, to a counter shaft 28. A second pulley 29, fixedly mounted on the counter shaft 28, transmits motion through the medium of a belt 30 and pulley 31, to the buffing wheel shaft 16. Shafts 16, 21 and 28 are all mounted, by means of pillow blocks 32, to the underside of the cover 12; however, as this is conventional design, no further description is considered necessary. The complete arrangement of shaft, belts and pulleys is shown to best advantage in Figure 3.

The buffing wheel shaft 16 protrudes through one of the sides 10, and has mounted on its remote end a buffing wheel 33. As will be seen from Figure 4, the buffing wheel 33 comprises flanges 34 and 35 fixedly mounted upon the shaft 16, and having a sponge rubber disc 36, clamped between them by means of a nut 37 which engages the threaded end of the shaft 16. A sleeve 38 limits the clamping effect of the nut 37. The rim of the wheel 33 is encased by a band of sand paper 39, or other suitable abrasive material.

Mounted on the upper side of the cover 12 are aligned pedestals 40 and 41. Pedestal 41 rotatably supports the driving chuck spindle 17, while pedestal 40 slidably supports a follower chuck spindle 42. The spindles 17 and 42, which are coaxial, are adapted to clamp an egg therebetween and revolve the same, as can be seen on Figure 6, where an egg E is indicated in phantom. The egg is resiliently held in alignment with the shafts 17 and 42 by means of a driving chuck 43 and a follower chuck 44. Chuck 43 is fixedly mounted on the inner end of the shaft 17 which stops short of the inner face thereof, to form a counter base 45 which is beveled to accommodate a rubber washer 46. The washer 46 has a concentric, backwardly protruding stem 47, with an enlarged shoulder 48, which

frictionally engages a hole 49 located in the end of the shaft 17.

The follower chuck 44, which is rotatably mounted on the inner end of the shaft 42, preferably by means of antifriction bearings 50, is counter bored on its inner face to receive an annular rubber washer 51, having its inner surface beveled to face and be in alignment with the washer 46.

The shaft 42 is adapted to slide axially in its mounting in the pedestal 40, and is held in a normally extended position as shown on Figure 5, by means of a compression spring 52 which surrounds the shaft 42 and acts between the face of the inner boss of the pedestal 40 and a collar 53 fixedly mounted on the shaft 42 adjacent the chuck 44. A handle 54, fixedly mounted on the outer end of the shaft 42, acts as a stop against the face of the outer boss of the pedestal 40 to limit the action of the spring 52.

The outer end of the shaft 17 has concentrically mounted thereon an end buffer comprising a flange 55 having an open ended bushing 56 screwed thereon. Inserted within the bushing 56 is an inner bushing 57 which has a groove 58 cut in the outer wall thereof. Diametrically opposed slots 59 are cut through the wall of the bushing 57 adjacent one edge of the groove 58. A disc of sand paper 60 or other suitable abrasive material, is adapted to cover the outer end of the bushing 57 remote from the slots 59, and has backwardly extending strips 61 which are threaded through the slots. A plug 62 of sponge rubber, is then inserted in the bushing, 57, and acts to form a cushion for the support of the disc 60, and also locks the strips 61 in place. The complete assembly is then inserted in the bushing 56, the strips 61 frictionally engaging the inner surface thereof, and maintaining the parts in assembled relationship.

Figure 8 discloses a buffer pad 62 comprising a block of sponge rubber 63 having a strip of abrasive material 64 wrapped around it.

In operation, any egg which is only slightly soiled, is quickly cleaned by holding it against the rotating wheel 33. An egg which requires more thorough cleaning is mounted as shown on Figure 6 by sliding shaft 42 against the action of the spring 52, by means of the handle 54. The egg is then firmly but lightly held in place between the resilient washers 46 and 51 and the motor started. The chuck 43 rotates the egg which in turn rotates the follower chuck 44 on its rotatable mounting. As the egg is rotated, it is cleaned by means of the pad 62 being held lightly against it.

After the egg is removed, any spots remaining on the ends may be removed by holding them against the end buffer as shown on Figure 7.

All buffing surfaces are resilient, so as not to damage the eggs, and also to accommodate them to the shape of the contacting part of the shell.

The chucks are adapted to maintain the egg in an aligned position while exerting a light pressure thereon. All moving parts are readily available by means of the hinged mounting features.

While we have disclosed a preferred embodiment of our device, it should be understood that modifications may be made within the spirit and scope of the appended claims.

We claim:

1. An egg cleaning machine comprising a base, a spindle rotatably mounted thereon, a second spindle mounted thereon in axial alignment with said first mentioned spindle, resiliently compressible egg holding device mounted on the adjacent ends of said spindles, and means to drive one of said spindles, the egg holding device on the other spindle being freely rotatable.

5 2. An egg cleaning machine comprising a rotatably mounted spindle, a slidably mounted non-rotatable spindle coaxial therewith, a driving chuck mounted on the end of the first spindle and a follower chuck rotatably mounted on the end of the other of said spindles.

15 3. An egg cleaning machine comprising a rotatably mounted spindle, a slidably mounted spindle in axial alignment therewith, an egg receiving chuck fixedly mounted on the first spindle, said chuck having a resilient egg receiving depression in the end thereof, and a second chuck having a resilient egg receiving depression in the end thereof rotatably mounted on the end of said slidably mounted spindle.

20 4. An egg cleaning machine comprising a rotatably mounted spindle, a slidably mounted non-rotatable spindle coaxial therewith, a driving chuck mounted on the end of the first spindle, a follower chuck rotatably mounted on the end of the other spindle, resilient means urging said second spindle toward the first spindle, and a cushioned socket in each chuck to engage an end of the egg.

25 5. An egg cleaning machine comprising a rotatably mounted spindle, a slidably mounted non-rotatable spindle coaxial therewith, a driving chuck mounted on the end of the first spindle, a follower chuck rotatably mounted on the end of the other spindle, resilient means urging said second spindle toward the first spindle, and a cushioned socket in each chuck to engage an end of the egg, and means to limit the sliding of said slidably mounted spindle toward the first spindle.

30 6. An egg cleaning machine comprising a rotatably mounted spindle, a slidably mounted non-rotatable spindle coaxial therewith, a driving chuck mounted on the end of the first spindle, a follower chuck rotatably mounted on the end of the other spindle, resilient means urging said second spindle toward the first spindle, and a cushioned socket in each chuck to engage an end of the egg, and means to limit the sliding of said slidably mounted spindle toward the first spindle.

35 LEONARD S. CRANMER.
